LAUNDRY MACHINE

James B. Kirby, West Richfield, Ohio, assignor
to The Apex Electrical Manufacturing Com-
pany, as trustee, Cleveland, Ohio, a corporation
of Ohio

Application March 2, 1949, Serial No. 79,261

3 Claims. (Cl. 68—23)

1

This invention relates to laundry machines and more particularly to a domestic laundry machine of the single tub washer-extractor type in which the clothes to be laundered are washed and thereafter centrifugally dried in a single container.

It is among the objects of my invention to provide a laundry machine of the single tub washer-extractor type, wherein the container for the clothes and fluid, and the motor and drive mechanism for washing and extracting is supported with respect to a base by laterally yieldable means secured to the unit above the motor and beneath the container and wherein the container is provided with a water balance device which retains a part of the fluid extracted from the clothes, the construction and arrangement being such that the yieldable supporting means lowers the critical speed of the container during extraction and the water balance device compensates for out of balance conditions that may occur above critical speed.

It is a further object of my invention to provide a laundry machine according to the preceding object, wherein the container is surrounded by a casing to receive washing fluid removed from the container and wherein the casing is provided with means to withdraw such washing fluid from the casing.

It is a further object of my invention to provide a laundry machine of the single tub washer-extractor type wherein the container for the clothes and fluid and the drive mechanism therefor comprises a unit that is supported on a base near the center of gravity of the unit on laterally yieldable supports and the base in turn is supported on the floor by laterally yieldable supports whereby the critical speed of the extractor is lowered.

It is a further object to provide a laundry machine according to the preceding object wherein the container includes a water balance device which retains a part of the fluid extracted from the clothes so as to compensate for out of balance conditions that may occur in the container during extraction.

It is a further object of my invention to provide a laundry machine wherein the clothes are washed in a container holding the clothes and laundry fluid by a motion imparted to the container such that parts of the container recipro-

cate vertically and having imparted thereto during the reciprocation thereof an acceleration exceeding the acceleration of gravity and wherein the container is thereafter rotated about the axis thereof to centrifugally extract the laundry fluid from the clothes and wherein the container supporting structure and power unit therefor are connected to provide for a low critical speed at the initiation of the extracting operation.

It is a further object of my invention to provide a laundry machine according to the preceding object wherein water extracted from the clothes is utilized to provide a balance for the container subsequent to the operation thereof through the critical speed of rotation referred to.

It is a further object of my invention to provide a machine according to the preceding objects wherein an out of balance condition occurring during the initiation of the extracting operation is automatically controlled by a de-clutching and braking operation that is effective to interrupt the acceleration of the extractor.

It is a further object of my invention to provide a machine according to the preceding object wherein the translatory movement of the extractor, with respect to the supporting structure for the machine, is utilized to effect the corrective de-clutching and braking action.

Other objects and advantages relating to the compactness, low cost of manufacture and portability of the laundry machine will appear from the following description and the appended drawings wherein:

Fig. 1 is a sectional view through the laundry machine showing the driving mechanism in an extracting position;

Fig. 1a is an enlarged sectional view showing in detail the upper part of the clothes container.

Fig. 2 is a sectional view taken on the line 2—2 of Fig. 1;

Fig. 3 is an elevation showing the manually and automatically operated parts of the clutch control for the driving mechanism;

Fig. 4 is an elevation showing the laundry machine tilted about its supporting wheels for convenient handling;

Fig. 5 is a sectional view including a detailed showing of the clutch control parts;

Fig. 6 is a sectional view with parts broken away of the clutch control; and

2

Fig. 7 is a sectional view of the clutch control parts taken normal to the sectional view of Fig. 5.

It is generally recognized by those familiar with the centrifugal extractor art that the major difficulty in the centrifugal extraction of laundry fluid from clothes results from the forces developed at the critical speed of rotation and that a low critical speed is to be desired. The attempts to achieve a low critical speed or counter-balance for the forces developed at critical speed have usually resulted in complicated and expensive mechanism unsuited to a small domestic laundry machine. According to my invention a low critical speed is obtained and the liquid extracted from the clothes is utilized in a water balance ring carried by the container which compensates for out of balance loads that may occur in the container above the critical speed thereof. The low critical speed is achieved according to my invention by the novel structure of the container for the clothes, the mounting therefor and the drive means herein disclosed. The machine in its entirety is indicated in Fig. 1 as at 5 and comprises a base 6 which supports the casing 7, which in turn supports the motor bell housing 8 and the drive assembly 9. The base 6 and the casing 7 are connected to each other and the distribution of the weight of the parts carried thereby is such that the entire machine 5 may be tilted about the wheels 10 at the lower edge of one side of the base and the machine can be wheeled about for storage in the manner of a hand truck. The tilting and wheeling the machine in this manner is facilitated by opposed handles 11 attached to the casing as indicated in Fig. 4. The lower flared edge 12 of the base serves as a pedal or abutment for the user's foot to assist in the tilting operation. The base 6, casing 7 and the container 13 disposed within the casing are preferably made of fiber glass because of the weight-strength ratio obtainable with this material. The base 6 comprises a hollow truncated-cone-like structure terminating at the top in an inturned supporting flange 14. The base 6 is provided at the side opposite the wheel supports with vacuum cups 15 which, along with the resilient tire 10a of the wheels 10, provide a resilient flexing support that restrains the machine against movement on the floor during operation. The base mounting 10-15 cooperates with structure hereinafter described to effect the low critical speed obtained during the initiation of the extracting operation.

The casing 7 is secured to the base 6 through the medium of four spaced vacuum cups as at 16. The cups 16 are similar to the cups 15 but are made up of a softer rubber composition and are more flexible than the cups 15. The open ends of the cups 16 are disposed within the complementary metal cups or pockets 17 carried by the flange 14 of the base 6 and a flexible tie such as the cable or rope 18 is anchored in the stem of the vacuum cups 16 at one end and anchored beneath the flange 14 of the base at the other end as at 19. The cups 15 and 16 are preferably provided with a small opening or air-bleed hole 20 which causes the cup under the loads imposed by the operation of the machine to function somewhat in the manner of a dashpot so as to dampen the movement of the relatively moving parts. The cups 15 and 16 are provided with the reduced cross-section as at 21 to increase the flexibility of the support with respect to the lateral or horizontal motion.

The container 13 comprises side walls 23, a bottom wall 24 and a reentrant hub 25. The side

walls 23 slope outwardly from the hub towards the top and are secured to the top section 26 of the container by spaced blocks 27 or the like to provide a discharge opening for the laundry fluid at the greatest diameter of the container. A plurality of inclined ribs are secured to the interior of the container 13 in the lower portions thereof to facilitate the roll-over and flexing of the clothes during washing. The upper section 26 of the container is curved inwardly and terminates in a down turned flange 28 which prevents the clothes from moving out of the container during extraction and which cooperates with the depending rim 29 carried by the casing of the top thereof to prevent the loss of fluid during washing.

A water balance chamber for the container is provided between the outer wall 23 of the container and the imperforate band 30 carried by the wall 23. The band 30 is spaced from and secured to the wall 23 by a plurality of vertically extending baffle plates 31 and 32 alternately arranged at spaced intervals around the periphery of the container. The vertical extent of the pockets formed by the baffles 31 and 32 is interrupted in part by the angle section 33. The pockets thus formed are open at the top as at 34 to receive the laundry liquid centrifugally discharged from the container during extraction and open at the bottom as at 35 to release such laundry fluid as the container comes to rest. The baffles 31 are cut away as at 36 to provide a fluid opening into the next adjacent pocket near the top of the water balance device and the baffles 32 are cut away as at 37 to provide a fluid passageway into the next adjacent pocket near the bottom of the water balance device.

The alternate top and bottom openings 36-37 meter or control the rate of flow peripherally of the liquid between the walls 23 and 30 of the container and water balance device respectively. For instance, it will be observed that peripheral flow between adjacent pockets is controlled by baffle plate 31 so as to flow through the passageway 36 at the top and that flow in the same direction with respect to the next adjacent baffle 32 would be limited mainly to movement around the bottom of the baffle 32 and through the opening or cut-away 37. This peripheral movement of the liquid requires movement of the liquid vertically through the pocket and the vertical motion is in turn limited to a volume or depth exceeding the horizontally extending baffles 33. In this manner surge effects are eliminated and the effect of the water balance is smooth and even.

It will be understood that when the container 13 is rotated, the washing fluid is centrifugally discharged over the upper wall thereof through the openings between the blocks 27 and that near the critical speed of such rotation the flexible band 38 is moved by the water and the centrifugal force of rotation so as to move upwardly from the upper edge of the container wall as at 23a so as to discharge laundry fluid into the pockets formed between the baffles 31 and 32. During washing the flexible band 38 maintains the position shown in Fig. 1 to prevent the loss of washing liquid. It will also be understood that as the rotational speed increases, the fluid disposed in the pockets between the baffles will move from one pocket to another so as to compensate for out of balance conditions that may occur as the extraction proceeds.

The hub portion 25 of the container is apertured adjacent the central axis thereof to receive the end of stub shaft 40 of the drive mechanism.

5

During the washing operation the stub shaft 40 describes a conical path but does not rotate on its own axis and thus progressively tilts the container to effect the Kirby method of washing. By the term Kirby method, as used herein, it will be understood that the container is progressively tilted about a point on the central axis thereof at a rate such that the bottom and side walls of the container are moved vertically with an acceleration exceeding the acceleration of gravity. This rate of movement results in a successive raising and lowering of the clothes and fluid, the lowering rate being such that the container portions supporting the clothes and fluid move downwardly at a rate exceeding the acceleration of such clothes and fluid due to gravity. On the return upward stroke the descending clothes and fluid violently collide with the ascending container part with the result that there is produced successively a condition of impact and cavitation. The flexing of the clothes by the Kirby method effects a rapid washing action and with the herein disclosed arrangement of washing ribs and the herein disclosed container configuration, the Kirby method of washing evenly distributes the clothes around the tub so that the washing operation arranges the clothes to minimize out of balance during extraction. In connection with the Kirby method of washing briefly described above, reference is made to my co-pending applications identified as follows: Ser. No. 526,154 filed March 13, 1944, entitled Method and Apparatus for Washing and Drying Clothes, now Pat. No. 2,520,366, Ser. No. 729,372 filed February 18, 1947, entitled Washing Machine, now Pat. No. 2,614,410, Ser. No. 760,555 filed July 12, 1947, entitled Combined Washing and Extracting Machine, now Pat. No. 2,645,917, Ser. No. 757,773 filed June 28, 1947, entitled Washing Machine; Ser. No. 6,911 filed February 7, 1948, entitled Vibration Controlled Washing Machine, Ser. No. 17,844 filed March 30, 1948, entitled Combined Washing Machine and Extractor, Ser. No. 41,210 filed July 29, 1948, entitled Combined Washing Machine and Extractor, Ser. No. 42,192 filed August 3, 1948, entitled Combined Washing Machine and Extractor, Ser. No. 619,849 filed October 2, 1945, entitled Washing Machine, and Ser. No. 671,779 filed May 23, 1946, entitled Washing and Extracting Machine, which disclose and claim various forms of machines adapted to carry out my method of washing.

The drive assembly 9 includes a vertically disposed pedestal 41 having a conical flange 42 intermediate its height adapted to be received within a conical reentrant portion 43 formed in the underside of the casing 7. A gasket 44 carried by the flange 42 insures a fluid tight fit with the casing 7 when the pedestal is drawn into position on the casing by the bolts 45 extending through collar 46 on the inside of the casing. Roller bearings 47 and 48 are mounted within the pedestal at the upper and lower ends respectively to provide an anti-friction mounting for the sleeve member 49. The upper end of the sleeve 49 is provided with an enlarged head 50 which supports anti-friction bearings 51 and 52 at an angle to the axis of the sleeve 49. The angle between the axis of the head 50 and the axis of the sleeve is preferably about four degrees and it will be understood that this angle determines the magnitude of the tilting of the container employed to carry out the washing operation. The lower end of the sleeve 49 is exteriorly threaded to receive the interiorly thread-

6

ed sleeve 53 which carries a bearing 54 for the shaft 59 extending vertically within the sleeve 49. The upper end of the shaft 59 is rounded, as shown at 60, and is provided with a transverse key 61 with the ends thereof disposed in vertical slots in stub shaft 40 to transmit the rotation of shaft 59 to the stub shaft 40 as in a universal joint. The arrangement above described is such that when the sleeve 49 is restrained from rotation about its axis and the shaft 59 is rotated, the container, which is secured to the stub shaft 40 by the nut 49a, will rotate the container about the axis 50a which is coincident with the axis of the container. When however, the shaft 59 is restrained from rotation and the sleeve 49 is rotated, the container will be progressively tilted to carry out the Kirby method of washing above described.

The selective drive of the sleeve 49 and shaft 59, to carry out the washing and extracting operations respectively, is accomplished by means of the clutch and brake arrangement carried at the lower end of the pedestal 41. The exterior of the sleeve 53, which is secured to the lower end of the sleeve 49, is provided with a bearing 62 to support for rotation the continuously driven pulley 63. The opposed faces of the pulley 63 serve as driving clutch parts so that when the upper face of the pulley, indicated in 64, is in contact with the driven clutch part 65 carried by the sleeve 49, the washing action is carried out and when the lower face 66 of the pulley 63 is in engagement with a driven clutch part 67 carried by the shaft 59, the extraction operation is carried out.

To determine which of the driven clutch parts 65 or 67 shall be engaged with the pulley, a shifter cage is provided. The shifter cage comprises upper and lower annular rings 70 and 71 respectively. The rings 70—71 are normally maintained at a fixed distance from each other by spaced posts 72. The posts 72 are riveted at their upper ends to the ring 70 as best shown in Figs. 5 and 6 and have reduced shank diameters at their lower ends extending through openings provided in the ring 71. The ring 71 is normally urged upwardly against the larger shank diameter of the posts 72 by springs 73 which are maintained in the position shown in Figs. 5 and 6 by an adjusting nut 75. Throughout the normal operation of the laundry machine the rings 70 and 71 are maintained in the position shown in Fig. 5 and are moved as a unit by moving the upper ring 70 by means of pins 92 carried by the shifter fork 83—84—85 adjacent its pivot on the bell housing. The inner ends of the pins 92 are secured to blocks 92a carried by the ring 70.

The lower ring 71 may be moved independently of the upper ring by similarly arranged pins 98 secured to blocks 99 carried by the lower ring 71.

The driven clutch parts 65 and 67 are proportioned with respect to the pulley faces 64 and 66 so as to project radially there beyond and overlap a portion of the clutch shifter rings 70 and 71. The result of this arrangement is that the driven clutch portions which overhang the pulley surfaces serve as a friction clutch and the portion which overhang the clutch shifter ring 70 and 71 serve as a friction brake.

In Figs. 1, 5 and 7 the clutch shifter is shown in its raised or "spin" position where ring 71 is free of the lower driven clutch part 67 so that said clutch part 67 is brought to bear against the

face 66 of the driving pulley 63 by the resilient clutch plate 67a. In this position of the shifter the ring 70 has lifted the driven clutch member 65 away from the face 64 of the pulley 63 in opposition to the resilient member 65a and thus the ring 70 serves as a brake to restrain the sleeve 49 from rotational movement. When the clutch shifter as a unit is moved to its lower position (not shown) it will be understood that the ring 71 will move the driven clutch member 67 down away from the face 66 of the pulley 63 and at the same time the clutch member 65 will be lowered into engagement with the face 64 of the driving pulley. This wobbles the container 13 to effect the washing action as above described. The clutch parts and the clutch shifter units, above described, are proportioned so that the rings 70 and 71 may be moved to an intermediate or neutral position whereby neither of the driven clutch member 65 and 67 are in frictional engagement with the driving pulley 63.

The drive for the machine includes a motor 13 supported by the bell shaped housing 8 secured to the underside of the casing 7 by means of cap screws 14 and the motor and driving assembly thus forms a flexibly supported unit with the casing 7. The belt 76 is arranged to transmit the rotation of the motor shaft to the driving pulley 63 by way of the idler pulleys 77 and 78. The last named pulleys are supported on an axis 30 transverse to the motor pulley by means of a bracket 79 secured to the bell housing 8. The pulleys 77 and 78 are secured to the bracket 79 at an angle determined by the belt 76. The bell housing is provided with a pair of opposed bosses 80—81 to which the clutch fork 84—85 is pivoted and the housing is vertically slotted as at 90 to accommodate the clutch shifting pins 92. In the normal operation of the machine the manual swinging of the clutch fork about pivot 91 on the bell housing raises and lowers the ring 70 by means of pins 92 extending inwardly from the diverging arms 84—85 of the clutch fork. The motion of the ring 70 is transmitted through posts 72 to raise and lower the clutch shifter assembly as a unit so as to engage one or the other of the driven clutch parts 65—67 with the rotating pulley 63. When, however, an extreme out of balance condition occurs during the acceleration of the container in the extraction phase it is desirable that the drive to the extractor be interrupted momentarily. The advantage of such momentary interruption or dwell during acceleration is that the mass of clothes and fluid causing the out of balance condition will have fluid extracted therefrom during such dwell and thus remove or reduce the cause of such condition. To effect the drive interruption or dwell, I have provided an independent control for the extractor clutch comprising the linkage mechanism 93, 94, 95 and 96. The link 93 is secured to a pin 98 extending through the vertical slot 90 of the bell housing and the inner end of the said pin 98 is anchored to a post 99 carried by the ring 71. The upper end of the link 93 is pivoted as at 100 to the bell crank 94 which in turn is pivoted on the bell housing as best shown in Figs. 3 and 7. The other end of the bell crank 94 is pivotally connected to the U-shaped member 95, shaped to embrace the bell housing, and the mid-portion of the member 95 is secured to a flexible element 96 anchored to a bracket 96a mounted on the base 6. During normal extraction operation of the machine, that is in the absence of an out of balance load developed when approaching

critical speed, the parts remain in the position shown in Fig. 5, wherein the flexible element 96 is slack. When, however, an out of balance condition occurs such as would cause the casing 7 to shift laterally with respect to the base 6, such relative movement away from the bracket 96a puts the flexible member 96 in tension which turns the bell crank 94 on its pivot with the result that the ring 71 is moved downwardly, as shown in Fig. 6. The downward movement of the ring 71 is accommodated by the springs 73 with the result that the ring 70 remains in its raised position as shown in Figs. 5 to 7 and the acceleration of the container is retarded by the declutching and braking effect of ring 71 on the driven clutch part 67. The translatory movement of the container toward the bracket 96a renders the springs 73 effective in restoring the ring 71 to its raised position as shown in Fig. 7.

The outer end of the clutch fork 83 projects through a vertical slot in the skirt 7a so that it may be conveniently manipulated by the operator. Inside of the skirt 7a and secured to the underside of the casing 7 as at 88 is a depending latch bar having reentrant grooves to receive a complementary boss carried by the fork 83 so as to resiliently hold the fork in either one of three positions corresponding to a washing, extracting or neutral position.

To carry out the laundry operation the clothes and washing fluid are placed within the container 13 along with soap or other detergents and the clutch shifter fork 83 is moved to the dotted line position 83a, as shown in Fig. 3, which results in lowering the clutch shifter assembly so that the ring 71 moves the driven clutch part 67 away from the rotating pulley 63 and at the same time restrains the member 67 and the shaft 59 carried thereby from rotation. The lowering of the clutch shifter ring 70 brings the driven clutch part 65 into engagement with the face 64 of the pulley 63 with the result that the rotation of the pulley is imparted through the clutch to the sleeve 49. The rotation of sleeve 49 effects a progressive tilting of the container and washes the clothes therein. It will be noted that the container 13 is imperforate and fluid tight up to the juncture of the wall 23 with the upper section 26 so that the clothes and washing fluid are retained therein during the washing operation. The yieldable rubber-like guard 29 depending from the top of the casing 7 prevents the splashing of the washing fluid over the upper edge of the container.

The driven clutch part 65 and the upper end portion 50 of sleeve 49 carry the counterweights W and W₁ respectively. Said weights are spaced 180 degrees from each other and function as a force couple to compensate for the load differential in raising and lowering the clothes and fluid.

At the conclusion of the washing operation the lever 83 is moved to the full line position shown in Fig. 3 which moves the clutch shifter parts and the driven clutch parts to the position shown in Fig. 1, wherein the rotation of the driving pulley 63 is transmitted to the shaft 59 so that the container is rotated about the axis 59a of the stub shaft. As the rotation of the container 13 increases up through the critical speed, the washing fluid is discharged from the container through 70 the openings between the blocks 27 and the discharged water directed downwardly into the pockets between the baffles 31 and 32 of the water balance ring. A part of the discharged water is centrifugally held in the annular chamber 75 between the wall 23 of the container and the

wall 30 of the balance device. The surplus water moves downwardly through the openings 35 around the bottom of the balance ring chamber into the casing 5 where it is discharged through the tangentially arranged conduit 7b. A hose 7c directs the discharged wash water to a drain. As the extraction phase continues there will be a change in the out of balance condition due to the water being removed from the clothes and such changes are compensated for by the flow of water through the water balance ring pockets heretofore described.

At the conclusion of the extracting operation the control lever 33 is moved to its intermediate or neutral position so that neither of the driven clutch members 65 or 67 is engaged with the rotating pulley. In this position the clutch parts are restrained from rotation by frictional contact with the rings 70-71. The bringing of the basket to rest eliminates the centrifugal force theretofore effective to hold the washing fluid against the wall 30 of the balance ring and such water is discharged by gravity into the casing 7 where it escapes through the outlet 7b.

In the event that the character of the garments being washed produces an extreme out of balance condition during the initiation of the extracting phase such as would tend to give the casing 7 and the mechanism carried thereby a shifting or translatory movement with respect to the supporting structure 6, the acceleration of the extractor will be interrupted. This interruption or momentary dwell of the acceleration causes the garments, which produced the out of balance condition, to lose some of the fluid by centrifugal extraction during such momentary dwell. Such loss of fluid reduces the total weight of the garments and the basket in its entirety may thereafter be further accelerated. This cycle of acceleration and momentary dwell will be automatically repeated as often as may be necessary until sufficient fluid is extracted from the garments so that the extractor basket may pass through its critical speed of rotation without causing appreciable translatory motion with respect to the base or supporting structure.

Although I have shown in the drawings and described in considerable detail one form of my invention, it will be appreciated by those skilled in the art that various modifications may be made therein without departing from the scope of my invention as defined in the following claims.

What is claimed is:

1. In a combined washing and extracting machine, a base, a supporting frame yieldingly supported on said base, a pedestal projecting upwardly from said supporting frame, a tubular shaft mounted for rotation in said pedestal, an inclined bearing fixed to the upper portion of said tubular shaft, a washing and extracting container having a re-entrant bottom portion provided with a depending stub shaft mounted in said inclined bearing, a spin shaft mounted for rotation within said tubular shaft coupled to said stub shaft, a motor support depending from said supporting frame, a motor secured to said motor support coaxially of said tubular shaft, transmission means mounted coaxially of said tubular shaft and means interconnecting said motor and said transmission means, a water balance ring secured to said washing and extracting container, said balance ring having an imperforate side wall secured to and spaced from the outer wall of the container to provide an annular chamber, vertically disposed spaced baffles arranged in said

annular chamber, the vertical extent of said baffles being less than the vertical extent of the said imperforate side wall so as to provide an interconnecting passageway between the pockets in the annular chamber formed by said baffles, said washing and extracting container having openings near the top of the container and below the top edge of the said imperforate wall of said balance ring whereby centrifugally discharged water from the container is moved through said openings into said annular chamber.

2. A washing and extracting machine comprising a base having side walls, an inwardly projecting support carried by said side walls, spaced resilient supporting members mounted on said inwardly extending support, a frame secured to said resilient supporting members, a vertically disposed pedestal mounted on said frame, a tubular shaft rotatably mounted in said pedestal, an inclined bearing secured to the upper end of said tubular shaft, a washing and extracting container having a re-entrant central bottom portion surrounding said pedestal and inclined bearing, a stub shaft secured to said container and depending therefrom and rotatably mounted in said inclined bearing, said container being in the form of a surface of revolution having a maximum diameter adjacent the top of the container, a balance ring in the form of a surface of revolution secured to the exterior wall of said container, said balance ring including an imperforate circular wall spaced from said container, said imperforate wall extending vertically above the maximum diameter of the container, said container wall having openings at said maximum diameter whereby water discharged centrifugally from the container is directed into said water balance ring, a transmission housing depending from the underside of said frame, transmission means concentric of said tubular shaft within said housing, a motor secured to said housing coaxially of said tubular shaft and means connecting said motor and said transmission means to rotate said container.

3. A washing and extracting machine comprising a floor supported base, resilient means anchored at one end to said base and at the other end to a frame, said resilient members being spaced from each other and providing for limited lateral movement of the frame with respect to the base, a vertically disposed pedestal secured to said frame and projecting above said frame, a tubular shaft rotatably mounted in said pedestal and projecting above the upper end of the pedestal and provided at said upper end with an inclined bearing, said tubular shaft projecting below the lower end of the pedestal and provided at said lower end with transmission means, a washing and extracting container having a re-entrant bottom portion surrounding said pedestal, a stub shaft mounted concentrically of the container in said re-entrant bottom portion and depending therefrom into said inclined bearing, a spin shaft mounted for rotation within said tubular shaft and having the upper end thereof connected to said depending stub shaft, a transmission housing secured to said frame and depending within said base centrally of the base, a motor mounted on the lower portion of said housing coaxially of said shafts and means operatively connecting said motor and said transmission means.
